UNITED STATES PATENT OFFICE.

MYRTIAN A. PECK, OF NASHVILLE, TENNESSEE, ASSIGNOR TO TENNESSEE OAK FLOORING COMPANY, OF NASHVILLE, TENNESSEE.

BUNDLE-TYING DEVICE.

1,176,092.

Specification of Letters Patent. Patented Mar. 21, 1916.

Application filed September 29, 1914. Serial No. 864,119.

To all whom it may concern:

Be it known that I, MYRTIAN A. PECK, a citizen of the United States, residing at Nashville, in the county of Davidson and 5 State of Tennessee, have invented certain new and useful Improvements in Bundle-Tying Devices; and I do hereby declare the following to be a full, clear, and exact description of the invention, such as will enable others skilled in the art to which it 10 appertains to make and use the same.

My invention relates to improvements in bundle tying machines for tying wire around bundles of lumber or other articles.

15 The objects of my improvement are, first, to provide a wire receiving and twisting head; second, to afford facility for imparting rotary movement thereto; third, to provide means to impart longitudinal movement to the twisting head during rotary movement thereof; fourth, to provide means for drawing the wire taut before twisting the same, and fifth, to provide means to normally hold a wire tightening and twisting 20 means at an inclined position prior to operation thereof.

I attain the above objects by the devices illustrated in the accompanying drawings described and claimed and the equivalents 25 thereof.

Referring to the drawings wherein like characters of reference denote similar parts throughout the several views: Figure 1 is a side elevation, with portions broken away, 30 of my improved bundle tying device. Fig. 2 is a detail taken on line 1-1 of Fig. 1. Fig. 3 is a detail taken on line 2-2 of Fig. 1. Fig. 4 is a plan view of the device. Fig. 5 is a longitudinal section of the wire-twisting head.

40 As is clearly shown in the drawings, the embodiment of the device which I have selected for the purpose of illustration consists in a base 1 suitably secured to a table or other object.

45 Fig. 2 is an offset arm, preferably integral with the base 1.

50 Fig. 3 designates a hinge-pin for pivotally connecting a hinged member 4 to the base 1. Hinged member 4 is provided with a cut-away portion 5, the sides of which are provided with the ways 6 adapted to slidably receive the wire-tightening block 7. This

block is provided with a wire-gripping device 8 of any suitable construction.

55 Fig. 9 designates an operating lever pivoted at its lower end to the ears 10, which ears depend from the hinged member 4. Lever 9 is preferably fork-shaped at its lower end and is provided with a pair of opposed slots 60 11 adapted to receive a pin 12 projecting from each side face of the reduced rear end 7' of the wire tightening block 7.

13 and 14 designate suitable bearings carried by hinged member 4 and adapted to 65 support a suitable wire receiving and twisting member. The wire receiving and twisting member consists of a spindle 15, pinion 16 fixed to the spindle, the spindle formed with a threaded portion 17, and a twisting 70 head 18. The twisting member is provided with a longitudinal eccentrically located wire-receiving opening 19 and an inclined wire-receiving hole 20, the front end of which is also eccentrically located with reference to the face of the head 18. This latter opening 20 extends only partly through the twisting-head 18. The spindle 15 is mounted in the bearing 13 and the screw-threaded portion 17 is threaded in the bearing 75 14.

The means for rotating the wire-twisting member consists of a segment-gear 21 adapted to mesh with pinion 16. The segment-gear is pivotally mounted upon a pin 85 22 extending from the bracket 23 carried by the hinged member 4. Segment-gear 21 is provided with a suitable operating lever or handle 24.

25 Fig. 4 designates a suitable compression 90 spring mounted on arm 2 and engaging at its upper end the hinged member 4 to normally cause the hinge-member to assume an inclined position, as shown in dotted lines in Fig. 1.

The angular end of the hinged member 4 is formed by means of a horizontally extending member 26 and a downwardly extending bracket 27 forms a corner to receive the articles to be tied. Member 27 is provided 100 with a hook 28. A foot pedal 29 is suspended from the hook 28. The operator may by putting his foot on the pedal, pull the hinged member into alignment with the base 1, thereby bringing the bundle-receiving corner into contact with the goods to be 105

tied, prior to twisting the wire which is pulled around the goods by the operator.

30 designates a pin secured to the hinged-member 4 spanning the opening 5 to act as 5 a guide for the wire.

The operation of the device is as follows: The wire is first pulled through the opening 8 of the sliding wire-tightening block 7, then through the longitudinal wire-receiving opening 19 of the twisting member, sufficient wire being pulled through to pass around the bundle to be tied. The hinged member is then lowered to bring the bundle-receiving corner into contact with the goods. 15 The wire is then pulled around the goods and passed through the inclined hole 20 of the twisting-head 18 and bent back as shown in Fig. 1 to lock the wire. The lever 9 is then pulled back, taking the slack out of the 20 wire and drawing it taut around the goods. Lever 24 is then turned through half of a revolution in the direction of the arrow, thereby rotating the head 18 and twisting the wires adjacent the end of the head 18. 25 During the rotary movement of the head and the twisting of the wire, the head 18 is caused by its screw-threaded portion 17 to move longitudinally, thereby withdrawing itself from the bundle as the wire is twisted. 30 The wire is then cut by any suitable means. After the wire has been severed, the lever 24 is moved back to its original position, bringing the head 18 back to its initial position ready for another operation.

35 Having thus described my invention, what I claim and desire to secure by Letters Patent is:

1. In a bundle tying machine, a hinged member, a wire tightening means, means for actuating said wire tightening means, a wire twisting member having a pair of eccentrically located wire receiving openings, said member having a threaded spindle engaging said hinged member, and means for 40 rotating and simultaneously retracting said wire twisting member.

2. In a bundle tying machine, a hinged member, a slidably mounted wire tightening block arranged on said hinged member, a lever adapted to actuate said block, a wire twisting head mounted on said hinged member, said head having a threaded spindle engaging said hinged member, and means for 45 rotating and moving said wire twisting head longitudinally in either direction.

3. In a bundle tying machine, a hinged member, a longitudinally movable wire-tightening block arranged on said hinged member, a lever adapted to actuate said

block, a wire-twisting head mounted on said 60 hinged member, means for rotating said wire-twisting head in either direction, and means for imparting longitudinal movement to the wire-twisting head simultaneously with the rotary movement imparted 65 thereto.

4. In a bundle tying machine, the combination with a base having an offset arm, a hinged member connected to said base, a wire-tightening block slidably mounted on 70 said hinged member, and an operating lever for moving said wire-tightening block; of a wire-twisting head having an eccentrically located longitudinal wire-receiving opening and an eccentrically located inclined wire-receiving hole, a slideable spindle integral with the wire-twisting head, a pinion fixed to said spindle, an internally threaded bearing fixed to the hinged member, a screw-thread formed on said spindle adapted to be received in said internally threaded bearing, a segment-gear pivotally mounted upon the hinged member adapted to mesh with said pinion, an operating lever 75 extending therefrom, a foot pedal depending from the hinged member, and a compression spring interposed between the offset arm and said hinged member, for the purpose set forth.

5. The combination with a base, a hinged member connected thereto, means to normally cause the hinged member to assume an inclined position, a wire-tightening block 90 slidably mounted on said hinged member, a lever for operating said wire-tightening 95 block, a bearing fixed to said hinged member, and an internally threaded bearing fixed to said hinged member, of a wire-twisting head, a spindle integral with said head and slidably mounted in said fixed 100 bearing, a pinion fixed to said spindle, a screw-thread formed on said spindle adapted to be receiving in said internally threaded fixed bearing, a segment-gear pivotally mounted on said hinged member, an operating 105 handle for said segment-gear, a bundle-receiving corner formed at the free end of said hinged member, and means for bringing said hinged member to a horizontal position and retaining it in such position 110 during the tying operation, substantially as set forth.

In testimony whereof, I affix my signature in presence of two witnesses.

MYRTIAN A. PECK.
